IMPACT TOOL WITH MAGNETIC BASE

Jack H. Brown, San Francisco, Calif.

Application October 29, 1956, Serial No. 618,990

2 Claims. (Cl. 29—81)

This invention relates in general to new and useful improvements in impact tools, and more specifically to an improved impact tool having a magnetic base for the mounting of the impact tool during use.

Aboard ship there is the continuous problem of keeping the steel plates of the ship clean and painted. Because of the action of the sea water, unless the surface of the ship's plates is absolutely clean when the new paint surface is applied, the plates will continue to rust beneath the new paint surface and as a result the new paint will eventually spall off. In order that the surface of the ship plates may be properly cleaned, at the present time it is necessary that the surface be cleaned with tripping hammers which are manually operated. The surface is then finally cleaned with a wire brush or the like. However, this requires a relatively great expenditure of manual labor which could be saved with an automatic machine.

It is therefore the primary object of this invention to provide an improved impact tool which is so constructed whereby it is effective in the operation of chipping paint and scale from ship's plates, the tool being provided with a plurality of impact heads which will strike the plates with only sufficient force to remove the paint and scale from the plate and in no way mark or mar the plates.

Another object of this invention is to provide an improved impact tool, the impact tool being primarily intended for removing paint and scale from steel plates and including a magnetic base whereby the impact tool may be self-supporting, the tool because of the magnetic base being suitable for chipping paint and scale on sides of ships and overheads of ships.

Another object of this invention is to provide an improved impact tool, the impact tool being provided with impact heads mounted on shafts, the shafts having associated therewith driving rods, the driving rods being reciprocated by crank means and having an effective stroke which is less than the travel of the impact head so that there is no direct mechanical connection between the driving rods and the impact heads at the time the impact heads strike a work surface thereby eliminating undesirable forces on the driving rods and the means for reciprocating the driving rods.

A further object of this invention is to provide an improved impact tool which is provided with a magnetic base, the impact tool being driven by an electric motor and the magnetic base being of the electro-magnetic type whereby the impact tool is highly portable and at the same time may be retained in position and may function by merely throwing a switch.

A still further object of this invention is to provide an improved impact tool, the impact tool including a crank which is resiliently mounted to permit the absorption of shock forces applied to the crank during the operation thereof and thus reducing damaging forces on the crank and connecting rods connected to the crank.

These together with other objects and advantages which will become subsequently apparent reside in the

2

details of construction and operation as more fully hereinafter described and claimed, reference being had to the accompanying drawings forming a part hereof, wherein like numerals refer to like parts throughout, and in which:

5 Figure 1 is a side elevational view of the impact tool which is the subject of this invention and shows generally the details thereof;

Figure 2 is an end view of the impact tool of Figure 1 and shows the driving connection between the electric

10 power unit of the impact tool and crank thereof, lowered positions of impact heads of the impact tool being shown by dotted lines;

Figure 3 is a bottom view of the impact tool taken substantially upon the plane indicated by the section line 15 3—3 of Figure 2 and shows the relationship of the various impact heads with respect to the magnetic base;

Figure 4 is a vertical sectional view taken substantially upon the plane indicated by the section line 4—4 of Figure 1 and shows the specific relationship between 20 the crank, the connecting rods, the driving rods, the impact heads and shafts supporting the impact heads;

Figure 5 is a transverse horizontal sectional view taken substantially upon the plane indicated by the section line 25 5—5 of Figure 1 and shows further the relationship of shafts for the impact heads and guide sleeves on which they are mounted for guided movement; and

Figure 6 is a perspective view of one of the impact heads and the shaft on which it is mounted.

Referring now to the drawings in detail, it will be 30 seen that there is illustrated the impact tool which is the subject of this invention, the impact tool being referred to in general by the reference numeral 10. The impact tool 10 includes a base, which is referred to in general by the reference numeral 12, and a supporting frame which is referred to in general by the reference numeral 14.

The supporting frame 14 includes a bottom plate 16 which is generally rectangular in outline. Extending upwardly from the bottom plate from positions adjacent 40 the corners thereof, as is best illustrated in Figure 5 is a plurality of vertical supports 18. The upper ends of the vertical supports 18 are connected to a top plate 20 which is similar to the bottom plate 16. The vertical supports 18 are connected together intermediate their 45 ends by an intermediate plate 22.

Secured to the outer faces of the vertical supports 18 at opposite ends of the supporting frame 14 are crank supporting plates 24. The crank supporting plates 24 have extending upwardly therefrom rods 26 which include intermediate journal portions 28. Slidably mounted on the journal portions 28 are bearing carrying bars 30. The bearing carrying bars 30 are positioned on the rods 26 by means of lower springs 32 disposed between the crank supporting plate 24 and the bearing carrying bars 30, and upper springs 34 telescoped over the upper part 50 of the rods 26 and bearing on the upper surfaces of the bearing carrying bars 30. The springs 32 and 34 are adjusted by means of collars 36 threadedly engaged on the upper ends of the rods 26 and locked in adjusted positions by means of set screws 38. By varying the positions of the collars 36, the tension of the springs 32 and 34 may be selectively varied to vary the shock dampening properties of the bearing carrying bars 30.

Carried by the bearing carrying bars 30 are aligned 55 bearings 40 in which there are mounted for rotation longitudinally extending cranks 42. In order that the cranks 42 may be driven, there is secured to the top plate 20 of the supporting frame 14 a power unit in the form of an electric motor 44. The electric motor 44 has connected thereto a flexible electric wire 46 so that the impact tool 10 may be readily moved from place to place during a work operation therewith. The oper-

ation of the electric motor 44 is controlled by means of a switch 48.

The electric motor 44 includes an armature shaft 50 which extends out through opposite ends thereof. Mounted on opposite ends of the armature shaft 50 are pulleys 52 and 54. The pulleys 52 and 54 are aligned with pulleys 56 and 58, respectively, of the cranks 42. Entrained over the pulleys 52 and 56 are drive belts 60. Similar drive belts 62 are entrained over the pulleys 54 and 58. It is pointed out at this time that the cranks 42 are identical and one of the cranks 42 may be substituted for the other by merely rotating it 180 degrees and placing it in position. By so making the cranks 42, the ends thereof may be offset as is illustrated in Figure 1 and still permit the interchangeability.

Carried by the intermediate plate 22, as is best illustrated in Figure 4, is a plurality of guide sleeves 64. The guide sleeves 64 are arranged in groups, there being one group of guide sleeves 64 for each of the cranks 42. Mounted in the upper part of each guide sleeve 64 for guided reciprocation is a driving rod 66. Connected to the upper end of each driving rod 66 by means of a pin 68 is a connecting rod 70. Each of the cranks 42 is provided with a plurality of throws 72, as is best illustrated in Figure 1. The throws 72 are so spaced whereby they are disposed on opposite sides of each of the connecting rods 46. Extending between the throws 72 is a journal pin 74 on which the upper end of each connecting rod 70 is mounted. Thus as the cranks 42 rotate, the driving rods 66 are reciprocated within the guides 64.

The bottom plate 16 is provided with bores 76 which are aligned with the guide sleeves 64. Slidably passing through the bores 76 are shafts 78. The upper ends of the shafts 78 are received in the lower ends of the guide sleeves 64 for guided reciprocatory movement. The lower ends of the shaft 78 are provided with impact heads 80. The impact heads 80 are disposed beneath the bottom plate 16 and have the upper parts thereof normally retained in engagement with the underside of the bottom plate 16 by the action of coil springs 82. The coil springs 82 are telescoped over intermediate portions of the shaft 78 and are retained in place by collars 84 removably pinned on the shaft 78. Thus the coil springs 82 serve to retain the impact heads 80 and the shaft 78 in a retracted position as illustrated in Figure 4.

As is best illustrated in Figures 2, 3 and 4, it will be seen that the base 12 is in the form of a pair of longitudinally extending blocks 86 disposed at opposite sides of the impact tool 10 and extending longitudinally thereof. The blocks 86 are of a desired height and support the impact heads 80 out of engagement with a work surface, such as the work surface 88 and at the same time to permit the driving rod 66 to move the impact heads 80 into striking engagement with the work surface 88. In order that the operator of the impact tool 10 need not support its weight during a working operation, there is mounted in each of the bars 86 powerful electro-magnets 90. The electro-magnets 90 will be of sufficient strength to support the impact tool during its operation either from a vertical surface or an overhead horizontal surface. Thus when the impact tool 10 is to be used in a chipping operation either on the side of a ship or an overhead of the ship, the electro-magnets 90 will be sufficient to support the impact tool in place once it has been positioned by the operator. The electro-magnets 90 are energized by means of a wire 92 which is connected to the lead wire 46 of the electric motor 44. If desired, the switch 48 for the operation of the electric motor 44 may control the energization of the electro-magnets 90.

Referring once again to Figure 4, it will be seen that for a major portion of its stroke, each driving rod 66 is disposed out of engagement with its associated shaft 78. Thus as the driving rod 66 approaches the lower end of

its stroke, it firmly comes into engagement with the upper ends of the associated shaft 78. Further, the effective length of the stroke of each driving rod 66 after its engagement with its respective shaft 78 is less than the distance between the impact head 80 and the work surface 88. By so arranging the components of the drive means of the impact head 80 it will be seen that there is no direct mechanical connection between the cranks 42 and the impact heads 80 at the time the impact heads 80 engage the work surface 88. However, the shaft 78 and the impact heads 80 are driven downwardly with sufficient force by the driving rod 66 to accomplish the desired operation. It is to be understood that the mating portions of the driving rods 66 and the shaft 78 will be formed of such material so as to prevent upsetting thereof.

At this time it is pointed out that two cranks 42 have been illustrated and that each of the cranks 42 drive four impact heads 80. If desired, the number of cranks 42 may be varied so as to be increased or decreased and each crank 42 may drive a greater or lesser number of impact heads. The only limitations placed upon the number of cranks 42 and the number of impact heads 80 is that the impact 10 should remain portable and readily handled by one man.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A portable impact tool comprising a supporting frame, a power unit supported by said frame, a plurality of parallel first guides carried by said frame, first shafts slidably mounted in said first guides, a plurality of second guides axially aligned with respective ones of said second guides, second shafts slidably mounted in said second guides, impact heads on said first shafts remote from said power unit, springs engaged with said first shafts and continuously urging said first shafts to retracted positions, a crankshaft, means carried by said frame supporting said crankshaft in transverse alignment with said second shafts, connecting rods connecting said second shafts to said crankshaft for continuous reciprocation and periodic engagement with said first shafts, and means connecting said drive unit to said crankshaft for rotating said crankshaft.

2. A portable impact tool comprising a supporting frame, a power unit supported by said frame, a plurality of parallel first guides carried by said frame, first shafts slidably mounted in said first guides, a plurality of second guides axially aligned with respective ones of said second guides, second shafts slidably mounted in said second guides, impact heads on said first shafts remote from said power unit, springs engaged with said first shafts and continuously urging said first shafts to retracted positions, a crankshaft, means carried by said frame supporting said crankshaft in transverse alignment with said second shafts, connecting rods connecting said second shafts to said crankshaft for continuous reciprocation and periodic engagement with said first shafts, means connecting said drive unit to said crankshaft for rotating said crankshaft, and a base on said frame remote from said power unit, said base being of the peripheral type and extending about said impact heads, said impact heads being entirely retracted within said base by said springs.
